UNITED STATES PATENT OFFICE.

WILLIAM PICKFORD AND EDWARD DERR, OF SEGUNDO, COLORADO.

IRONING-BOARD.

No. 856,490.

Specification of Letters Patent.

Patented June 11, 1907.

Application filed March 8, 1907. Serial No. 361,360.

To all whom it may concern:

Be it known that we, WILLIAM PICKFORD and EDWARD DERR, citizens of the United States, residing at Segundo, in the county of 5 Las Animas and State of Colorado, have invented a new and useful Ironing-Board, of which the following is a specification.

This invention relates to ironing boards and its object is to provide foldable devices 10 of this character which are simple, durable and efficient in construction and which can be readily adjusted to different elevations.

With these and other objects in view the invention consists of certain novel features of 15 construction and combinations of parts which will be hereinafter more fully described and pointed out in the claims.

In the accompanying drawings is shown 20 the preferred form of the invention.

In said drawings: Figure 1 is a perspective view of the device in position for use; Fig. 2 is a side elevation showing the device folded; and Fig. 3 is an enlarged section on line $x-x$, Fig. 2.

Referring to the figures by characters of 25 reference, 1 is the main board of the device which may be of any desired size or contour and has a cross plate 2 secured to the bottom face thereof near one end and provided with 30 downwardly turned ears 3. Pivot bolts 4 extend through these ears and mounted upon these bolts and between the ears are diverging supports 5 suitably connected or braced near their lower ends as shown at 6. An- 35 other set of diverging supports 7 is pivotally mounted on the bolts 4 and upon the outer faces of the ears 3 and these supports are also connected by a cross brace 8. The supports 5 and 7 are so proportioned that when the de- 40 vice is folded said supports 5 assume posi- tions between the supports 7. Any suitable means such as nuts 9 may be provided for holding the bolts 4 against displacement. Each of the supports 5 and 7 has an opening 45 10 therein and threaded through these open- ings is a flexible adjusting device 11 in the form of a rope, or other suitable flexible connection. A loop 12 may be formed at one 50 end of this connection to receive the other end of said connection in which a number of knots 13 may be formed. These knots are 55 adapted to prevent the end of the connection from slipping through the loop 12 and ob- 60 viously by manipulating this connection so

as to place different knots in engagement with 55 the loop the supports 5 and 7 can be held at desired distances apart so as to hold the board at any suitable distance from the floor. Ob- 65 viously if a chain is employed in lieu of a rope such as shown a hook could be connect- 6c ed to it for engaging the links instead of knot- 70 ting and looping the connection in the man- ner shown. This construction is so obvious 75 that it is not deemed necessary to illustrate it.

In order that the board 1 may be held in 65 a horizontal position after it has been ad- justed to a desired height a rope, chain or other flexible device 14 is placed in engage- 70 ment with the supports 5 and is adapted to detachably engage a hook 15 extending from 75 one end of the board. When this device is formed of heavy rope the same is provided with knots as shown at 16 to prevent it from slipping through the hook, but if it should consist of a chain it is obvious that any of 80 the links of the chain could be placed in en- gagement with the hook and no knots would be necessary.

A spacing block 17 is secured on one end 80 of the board 1 and an auxiliary board 18 is hinged upon and adapted to be supported by this block. The board 18 is designed for use in ironing sleeves and small garments, and when not in use it can be swung out of 85 the way over the end of the board 1.

It will be noted that when the device is not in use it can be folded into a compact bundle as shown in Fig. 2. Importance is attached to the simple means for adjusting the board vertically as it dispenses with the use of 90 hinges, bolts and the like such as have heretofore been found necessary in order to se- 95 cure a proper adjustment.

What is claimed is:

1. An ironing board comprising pivotally 95 connected supports, a flexible adjusting and holding device loosely engaging the supports, said device having means at the ends thereof for holding said ends together, a board piv- 100 tally mounted on the supports, and a flexi- 105 ble device for adjustably connecting the board with one of the supports.

2. An ironing board comprising foldable supports, flexible means loosely engaging the supports and having its ends adjustably con- 105 nected for holding the supports in predeter- 110 mined positions, a board pivotally mounted on the supports, a flexible holding device

connected to one of the supports, and means upon the board for adjustably engaging said device.

3. The combination with a board having 5 depending ears; of supports pivotally mounted upon the inner and outer faces of the ears respectively, one of said supports being foldable into the other support, flexible means loosely engaging the supports and having its 10 ends adjustably connected for limiting the movement of the supports away from each

other, and a flexible holding device upon one of the supports and adjustably engaging the board.

In testimony that we claim the foregoing 15 as our own, we have hereto affixed our signatures in the presence of two witnesses.

WILLIAM PICKFORD.
EDWARD DERR.
